UNITED STATES PATENT OFFICE

WILLIAM C. H. KLOPP, OF MAYWOOD, ILLINOIS

LAMP-SHADE-SECURING DEVICE

Application filed May 24, 1930. Serial No. 455,401.

This invention relates to lamp shade securing devices, the primary object of the invention being to provide a quick detachable shade holder, which will permit of the lamp shade secured thereby, being removed, without the use of tools.

An important object of the invention is to provide a device of this character embodying a stem to be secured on the threaded end of the usual lamp socket supporting bolt, and spring fingers carried by the body portion of the device to frictionally engage the stem to hold the device in position.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a lamp equipped with a shade securing device constructed in accordance with the invention.

Figure 2 is an elevational view of the shade securing device.

Figure 3 is a longitudinal sectional view through the securing cap.

Figure 4 is a longitudinal sectional view illustrating the cap and spring fingers in section.

Figure 5 is an elevational view of the body portion of the lamp sockets showing the stem on which the shade is mounted, in elevation.

Figure 6 is a sectional view taken on line 6—6 of Figure 4.

Figure 7 is a perspective view of the spring fingers.

Figure 8 is a longitudinal sectional view through the cap, illustrating the spring fingers as gripping the stem.

Figure 9 is an enlarged sectional view through the device.

Referring to the drawings in detail, the reference character 5 designates the base of a floor lamp which is provided with the usual bolt 6 formed with threads at its upper end to

receive the usual nut employed in securing the lamp shade in position.

In the present showing, the body portion of the sockets is indicated by the reference character 7, and through which the bolt 6 extends. The reference character 8 designates the upper shade ring which is of a size to closely fit against the body portion 7. Disposed above the body portion 7, is a stem 9 that is provided with a threaded bore to receive the bolt 6, as clearly shown by Figure 4 of the drawings, the stem being of a diameter to receive the ring 8.

The upper end of the stem 9 is tapered as at 10, so that the spring fingers 11, to be hereinafter more fully described, may slide over the stem readily. A groove 12 is formed in the stem at a point in spaced relation with the free end of the stem, the groove being of a construction to receive the ends 13 of the spring fingers.

These spring fingers are formed with offset portions 14, which lend resiliency to the fingers to cause the fingers to securely grip the stem over which they are positioned. It will further be seen that the fingers are formed with substantially straight portions 15 that contact with the stem, at points adjacent to the free end of the stem.

The spring fingers are secured within the cap 16 by means of the screw 17 which is disposed substantially centrally of the end of the cap. The lower end of the cap is closed by means of the end piece 18, so that the cap is held against wobbling while in use.

In the form of the invention as shown by Figure 8, the end member, which is indicated by the reference character 19, provides a support for the shade holding member 20.

From the foregoing it will be obvious that due to this construction, the cap may be readily pulled upwardly, causing the spring fingers to spread as they move out of the groove 12, allowing the cap to be slid from its position on the stem and permitting the lamp shade which is secured by the cap, to be lifted off of the stem.

It will of course be seen that when it is desired to position a lamp shade, the cap

may be placed over the stem and the spring fingers moved to grip the stem.

I claim:

1. A lamp shade securing device comprising a stem having a groove formed therein, a cap, spring fingers on the cap and adapted to engage within the groove to hold the cap in position, and said cap adapted to secure a shade on a lamp base.
2. A lamp shade securing device comprising a stem, said stem having a groove, a cap fitted over the stem and adapted to engage a lamp shade supporting ring, and yieldable fingers secured within the cap and adapted to engage within the groove to secure the cap in position.
3. A lamp shade securing device comprising a stem having a tapered extremity, a cap to be fitted over the stem to engage a lamp shade positioned thereover, yieldable fingers carried by the cap and adapted to spread when the cap is forced over the tapered end of the stem, and said fingers adapted to grip the stem to removably secure the cap in position.
4. A lamp shade securing device comprising a stem, a cap positioned over the stem and adapted to engage a lamp shade to secure the shade in position, spring fingers secured within the cap and having offset portions to engage the stem to removably secure the cap on the stem, and said fingers having substantially straight portions for gripping the stem adjacent to the free end thereof to prevent tilting of the cap.

In testimony that I claim the foregoing as my own, I have hereto affixed my signature.

WILLIAM C. H. KLOPP.
